[57] CLAIM

The ornamental design for a handle grip, as shown and as described.

DESCRIPTION

FIG. 1 is a front left perspective view of the handle grip of the present invention and the surrounding environment. The surrounding environment is shown in phantom, and is for illustrative purposes only and forms no part of the claimed design;

FIG. 2 is a front left perspective view of the handle grip of FIG. 1;

FIG. 3 is a left side elevational view of the handle grip of FIG. 1;

FIG. 4 is a right side elevational view of the handle grip of FIG. 1;

FIG. 5 is a front elevational view of the handle grip of FIG. 1;

FIG. 6 is a rear elevational view of the handle grip of FIG. 1;

FIG. 7 is a top plan view of the handle grip of FIG. 1; and,

FIG. 8 is a bottom plan view of the handle grip of FIG. 1.

FIGS. 2-8 are shown on a enlarged scale.
